US0D1066356S

(12) **United States Design Patent** (10) **Patent No.:** **US D1,066,356 S**
Toth et al. (45) **Date of Patent:** **** Mar. 11, 2025**

(54) **DISPLAY SCREEN WITH GRAPHICAL USER INTERFACE**

(71) Applicant: **Liberty Mutual Insurance Company**,
 Boston, MA (US)

(72) Inventors: **Stephen Joseph Toth**, Boston, MA
 (US); **Linnae Dawn Selinga**, Hampton,
 NH (US)

(73) Assignee: **LIBERTY MUTUAL INSURANCE
 COMPANY**, Boston, MA (US)

(**) Term: **15 Years**

(21) Appl. No.: **29/770,509**

(22) Filed: **Feb. 12, 2021**

Related U.S. Application Data

(63) Continuation of application No. 29/750,634, filed on
 Sep. 15, 2020, now Pat. No. Des. 1,007,519.

(57) **CLAIM**

The ornamental design for a display screen with graphical user interface as shown and described.

DESCRIPTION

The FIGURE is a front view of a display screen with graphical user interface showing the new design.

The outermost broken line perimeter illustrates a display, screen, or the like or portion thereof and forms no part of the claimed design. All other broken lines depict features of a display screen with graphical user interface that form no part of the claimed design.
